UNITED STATES PATENT OFFICE

2,656,556

SHOE SUPPORT

Richard A. Unger, Beverly, Mass., assignor to
 United Shoe Machinery Corporation, Flemington, N. J., a corporation of New Jersey

Application October 10, 1952, Serial No. 313,998

6 Claims. (Cl. 12—127)

1

This invention relates to machines for use in the manufacture of shoes, and more particularly to means for supporting the shoes while they are being operated upon. The invention is illustrated as embodied in a shoe supporting jack for a machine for leveling the bottoms of shoes progressively but it is to be understood that it is not thus limited in its applicability.

In leveling machines of the type above referred to, the heel end of the last is commonly supported by a tipping block carrying a spindle arranged to enter the spindle hole of the last, and by a pin in the tipping block having a last engaging head, the pin being automatically adjusted heightwise during tipping of the block in jacking the shoe to provide adequate support for the heel end of the last as illustrated and described fully in Letters Patent of the United States 1,831,109 granted November 10, 1931, on an application of F. V. Hart et al.

Different types of lasts require different sizes of spindles in order that a proper fit be obtained and that the shoe be adequately supported in the jack. For example, the spindle holes in lasts for children's shoes may be smaller than those in lasts for men's shoes and there may be variations in sizes of the spindle holes for different types of lasts for men's shoes etc. Accordingly, to adapt the machine for operation on shoes of all types, the spindles are replaceable and heretofore it has been customary to provide a locking screw for holding the spindle in the tipping block against accidental removal when the shoe is removed from the jack at the completion of the leveling operation.

To facilitate replacement of the spindles, it is an object of the present invention to provide improved means for locking the spindle in the tipping block. To this end and in accordance with a feature of the invention, the spindle locking means is controlled by the supporting pin and is so arranged that the spindle is free for removal by the operator in response to lifting of the supporting pin. The locking means also acts, in accordance with a further feature of the invention, to prevent rotation of the supporting pin so that its head remains in the proper position with respect to the tipping block.

The above and other features of the invention, including various details of construction and novel combinations of parts, will now be described with reference to the drawing and pointed out in the claims.

In the drawing,

Fig. 1 is a view in side elevation, partly in sec-

2

tion, of one form of leveling machine jack in which the invention is embodied;

Fig. 2 is a vertical section through the tipping block illustrating the locking means by which the spindle is retained therein against accidental removal; and

Fig. 3 is a view similar to Fig. 2 but illustrating the release of the locking means by upward movement of the supporting pin, with the spindle partially removed.

The invention is illustrated as embodied in a leveling machine jack of the type illustrated and described in Letters Patent of the United States 2,104,739, granted January 11, 1938, on an application of A. Eppler et al.

This jack comprises a heel post 10 and a toe post 12 carrying means for supporting a shoe and last for a leveling operation performed by a roll 14 which applies downward pressure on the shoe sole and acts progressively along the shoe bottom as the jack is swung by power operated means in directions lengthwise of the shoe.

Pivoted on a pin 16 in the upper end of the heel post 10 is a tipping block 18 carrying a spindle 20 which enters the spindle hole in the heel end of the last. The block 18 is arranged to be swung about the pivot pin 16 during jacking of the shoe to force the toe end of the shoe into engagement with a toe support 22 carried by the toe post 12. Additional supporting means are provided for the shoe between the heel and toe ends thereof comprising a cone support 24 arranged to be depressed by engagement of the cone of the last therewith in the jacking operation and subsequently to be forced upwardly against the shoe as described in detail in the Eppler et al. patent.

Further to assist in supporting the last and shoe against the heavy leveling pressure, the top face of the heel end portion of the last is supported by a pin 26 having a last engaging head 28, as illustrated in the Hart et al. patent referred to above. This pin is slidable in a bore in the tipping block 18, the lower end of the pin normally engaging an inclined surface 29 formed at the upper end of the heel post 10 so that the pin is automatically moved heightwise during tipping of the block 18 to maintain its proper supporting relation to the last. As shown in Figs. 2 and 3, the spindle 20 has an enlarged portion 30 on its lower end arranged to fit closely within a recess 32 in the tipping block adjacent to the supporting pin 26. It will be understood that the lower portions of the different sized spindles which may be

employed will be of uniform diameter properly to fit into the tipping block.

Formed in the tipping block and extending laterally therethrough between the recess 32 and the supporting pin 26 is a slot 34 to receive a roll 36. This roll is arranged to engage a flat surface 38 on the supporting pin 26, as shown in Fig. 2, to prevent rotation of the supporting pin thereby maintaining the head 28 in the proper angular relation with respect to the tipping block and to the last. The adjacent surface of the enlarged portion 30 of the spindle is provided with a flat surface 39 inclined upwardly and inwardly as illustrated in Figs. 2 and 3 and forming a recess for receiving the roll 36 so that with the parts in the positions shown in Fig. 2, the roll prevents removal of the spindle 20 from the tipping block without in any way interfering with vertical movements of the supporting pin during the jacking of the shoe.

A recess 40 is formed in the supporting pin 26 at the lower extremity of the flat portion 38 to receive the roll 36. This recess registers with the roll 36 upon upward movement of the supporting pin 26 into the position shown in Fig. 3. If the operator moves the spindle 20 upward with the pin 26 in this position, the roll 36 is cammed by the inclined surface at the lower end of the spindle into the recess 40 whereupon it no longer prevents upward movement of the spindle and removal thereof for replacement by another spindle of appropriate size. The roll 36 and the pivot pin 16 are normally held in the block 18 by a U-shaped clamping spring 42 the lower ends of which engage the ends of the pivot pin 16 and the legs of which engage the ends of the roll 36.

It will be understood that the roll 36 serves two important functions, one of which is to lock the spindle in the tipping block until the supporting pin 26 is moved upwardly by the operator into the position shown in Fig. 3 and the second function of which is to prevent turning of the supporting pin in the tipping block so that the head 28 remains in proper relation to the block. By this arrangement the operator is able very rapidly and with little effort to substitute one spindle for another in the jack as occasion requires.

Having thus described my invention what I claim as new and desire to secure by Letters Patent of the United States is:

1. Shoe supporting means comprising a block having a recess in its upper surface, a last spindle removably seated in said recess and projecting upwardly therefrom, a vertically movable pin carried by said block adjacent to said recess, and means controlled by said pin for locking said spindle in said recess.

2. Shoe supporting means comprising a block, a last spindle removably carried by and projecting upwardly from said block and arranged to enter the spindle hole of a last, a pin slideable in said block, said pin having a head adapted to engage and support the top of the heel end of the last, and means controlled by said pin for locking the spindle in the block.

3. Shoe supporting means comprising a block, a last spindle removably carried by and projecting upwardly from said block and arranged to enter the spindle hole of a last, a pin slideable in said block, said pin having a head adapted to engage and support the top of the heel end of the last, and means controlled by said pin for locking the spindle in the block, said pin having a surface engaging said locking means to maintain the locking means in locking position with the pin in operative position.

4. Shoe supporting means comprising a block having a recess in its upper surface, a last spindle removably seated in said recess and projecting upwardly therefrom, the lower end of said spindle having a recess in its side, a roll extending transversely through said block adjacent to the lower end of said spindle and arranged to enter the recess in the lower end of the spindle and last supporting means carried by said block and operative to maintain the roll in said recess in locking engagement with said spindle with the supporting means in operative position and to release the roll from locking engagement with the spindle with the supporting means moved into an inoperative position.

5. Shoe supporting means comprising a block having a recess in its upper surface, a last spindle removably seated in said recess and projecting upwardly therefrom, the lower end of said spindle having a recess in its side, a roll extending transversely through said block adjacent to the lower end of said spindle and arranged to enter the recess in said spindle, a last supporting pin carried by said block and arranged normally to engage the roll and to hold it in said recess in locking engagement with said spindle, said pin having a recess in its surface arranged to receive the roll with the pin withdrawn to a predetermined position thereby to free the spindle for withdrawal from the block.

6. Shoe supporting means comprising a block having a recess in its upper surface, a last spindle removably seated in said recess and projecting upwardly therefrom, the lower end of said spindle having an upwardly and inwardly inclined flat surface, a roll extending transversely through said block adjacent to the lower end of said spindle and arranged to engage the flat surface thereon, a last supporting pin carried by said block and arranged normally to engage the roll and to hold it in locking engagement with said spindle, said pin having a recess in its surface arranged to receive the roll with the pin withdrawn to a predetermined position thereby to free the spindle for withdrawal from the block, said last supporting pin having a flat surface arranged to be engaged by said roll with the supporting pin in operative position whereby the pin is prevented from turning in the block.
